UNITED STATES PATENT OFFICE.

ERICH PUSINELLI, OF NEW YORK, N. Y.

COIN-CONTAINER.

1,163,173.

Specification of Letters Patent. Patented Dec. 7, 1915.

Application filed March 5, 1915. Serial No. 12,262.

To all whom it may concern:

Be it known that I, ERICH PUSINELLI, a subject of the Emperor of Germany, and a resident of the city of New York, in the county of New York and State of New York, have invented certain new and useful Improvements in Coin-Containers, of which the following is a specification.

This invention relates to improvements in coin containers and particularly such as may be combined with articles of personal adornment and wear.

One of the objects of the invention is to provide means for carrying the smaller coins, as pennies, dimes, and nickels, in a particularly convenient manner and in which they are readily accessible and at the same time secured against accident or loss.

Another object is to combine with the coin container, a bracelet such as are commonly worn by ladies and gentlemen.

A further object is to provide such containing means in a useful design, subject to ornament and which may be produced at a moderate cost.

These and other objects, such as are more fully described, are attained by the novel construction and combination of parts hereinafter described and shown in the annexed drawings, forming part of this specification, and in which:—

Figure 1 is a general perspective view of the coin holder showing its application and purpose. Fig. 2 is a front view of the same, the cover being removed. Fig. 3 is a similar plan view showing the cover in position. Fig. 4 is a transverse sectional view taken on line 4—4 of Fig. 2. Fig. 5 is a side view of the same. Fig. 6 is an enlarged fragmental view of the cover and frame. Fig. 7 is a view showing the method of attaching the holder to the bracelet. Fig. 8 is a plan view showing a modification in construction. Fig. 9 is a plan view of the same, the cover being shown in position. Fig. 10 is a sectional view taken on line 10—10 of Fig. 9. Fig. 11 is a front view of the same.

As will be obvious from an inspection of the drawings this device is adapted to be applied to the wrist of the wearer in the same manner as certain other bracelets containing watches, vanity boxes and other articles of personal use or adornment, the coins being readily accessible and operatable by the other hand of the wearer.

In the device as indicated, the bracelet

and its attaching means may be of any size whatever, preferably being so arranged as to be flexibly held in position the holder being maintained in such manner as to be free from release through inadvertent action or movement of the wearer's hand.

To the outer or exposed part of the bracelet at the center is positioned the coin container, the same being of thin construction so as to interfere as little as possible with the convenience of the wearer. In conformity therefore the device is contrived to contain only sufficient coins for immediate use, such as car-fares, papers, magazines and the like, requiring but a relatively small expenditure, although obviously the container can be made as large as may be considered desirable.

The device shown is intended to hold pennies, nickels and dimes, and also the smaller coins as used in foreign countries, more readily and speedily accessible than where it is necessary to open a purse and extract money therefrom, the coin desired becoming immediately accessible and without disturbing the others within the container. Obviously it is equally convenient to insert coins in their proper place where they are held without danger of loss or displacement.

The bracelet 10 may have one end 11 permanently engaged with the wall 15 of the receptacle, the other end 12 having a snap fastening 13 as shown, or both may be securely and permanently engaged with the walls as may be desired.

The walls 15 are turned inward, as at 16, and joined by semicircular members 17 forming individual compartments 18 for the several coins which are pressed outwardly by spirally wound springs 19 against a fixed cover plate 20 provided with slotted openings 21 extending inward from the edge directly over the coin compartments 18, the openings being of lesser magnitude than the coins, the walls and the springs all being affixed to a base plate 22.

A revoluble cover 23 is pivoted to the fixed cover in such manner that the opening 24 therein may be brought into registration with any of the openings 21, permitting the entrance of a finger in sliding the coin outward so as to be grasped by the thumb and finger.

In order that correct registration of the openings may be effected and also that the revoluble cover may be held in any of its

adjusted positions, including that of non-delivery, a plurality of depressions 25 are formed in the cover 23, the same being adapted to snap into engagement with depressions 26 in the fixed cover, so that upon rotating the outer cover the depressions will engage and normally hold the cover either in operative position, allowing any selected coin to be withdrawn or in such position as to prevent withdrawal as shown in Fig. 3.

In the adaptation shown in Figs. 8 to 11 inclusive, the bracelet is engaged in a similar manner with the walls 15 which are secured to the base 22 but the partition walls 28 are free at their outer ends and formed of spring material in such manner as to embrace the several coins, holding them against displacement, and dispensing with the push springs entirely.

Having thus described my invention and ascertained the manner of its operations and use, what I claim as new and desire to secure by Letters Patent is:—

1. A wrist carried holder comprising a bracelet, a shallow annular receptacle combined therewith, resilient walls forming compartments in said receptacle and a rotatable cover pivoted centrally on said receptacle, said cover having an opening registerable with any of the mentioned compartments.

2. A wrist carried coin holder comprising a bracelet, a thin circular receptacle formed therewith, partitions within said receptacle attached at the center thereof and free at

their outer ends forming independent coin holders; a cover rotatably mounted on said receptacle, said cover having a single open slot registerable with any of the coin holders and means for resiliently maintaining said cover in such registered position.

3. A wrist carried coin holder comprising a bracelet, a thin circular container combined therewith, interior walls in said container forming compartments having openings toward the periphery of said container, the walls being slightly contracted near said openings, a cover rotatably mounted on said container having a recessed flanged edge surrounding said cover, and engaging the walls of said container, the recess being registerable with any of the said openings, said cover having a slot inwardly from the recess through which coins are operable.

4. A wrist carried coin holder comprising a bracelet, a coin receptacle containing compartments combined therewith, a fixed cover having recesses registering with the mentioned compartments, a movable cover rotatably engaged with said fixed cover and means for limitedly restraining the movement of said movable cover.

Signed at New York in the county of New York and State of New York this twenty-fourth day of February A. D. 1915.

ERICH PUSINELLI.
